EXERCISING DEVICE

Raymond E. Stephens, 9616 Greenview Drive,
St. Louis, Mo.

Filed Jan. 12, 1962, Ser. No. 68,295

Term of patent 14 years

(Cl. D34—5)

FIG. 2.

FIG. 1.

FIG. 3.

FIG. 1 is a front elevational view of an arm and hand exercising device, showing my new design.

FIG. 2 is a top view of the exercising device.

FIG. 3 is a side view of the exercising device.

The undisclosed side of the exercising device is substantially the same in appearance as the side shown.

I claim:

The ornamental design for an exercising device, substantially as shown and described.
